CARD INDEX TRAY

Paul O. Unger, Chicago, Ill., assignor to Wilson-Jones Company, Chicago, Ill., a corporation of Massachusetts

Application April 28, 1931, Serial No. 533,468

13 Claims. (Cl. 129—16)

This invention relates to a card index tray and concerns itself with a novel structure in which card spacing members are longitudinally adjustable in the trays, and are compressed into compact form by an adjustable follower block. The spacing members are preferably so designed that the card holder may be readily snapped thereon and readily removed therefrom. Other novel features of construction will become apparent in the following description.

The invention comprises the novel structure and combination of parts hereinafter described and more particularly pointed out and defined in the appended claims.

15 In the accompanying drawings which illustrate a preferred form of this invention, and in which similar reference numerals refer to similar features in the different views:

Figure 1 is an elevational view of a card index cabinet containing card index trays involving this invention; one tray being shown in dotted line in its withdrawn position.

Figure 2 is an elevational view with parts shown in section of one form of a card holder spacing member that may be used.

Figure 3 is a sectional view taken upon the line III—III of Figure 2.

Figure 4 is a top plan view of a card index tray involving this invention.

30 Figure 5 is an enlarged sectional view taken upon the line V—V of Figure 4 illustrating a card in elevated position.

Figure 6 is an enlarged sectional view taken upon the line VI—VI of Figure 4 illustrating a card in elevation.

Figure 7 is an elevational view of another form of spacer which may be used in the tray.

Figure 8 is a sectional view taken upon the line VIII—VIII of Figure 7.

40 Figure 9 is a sectional view taken upon the line IX—IX of Figure 7.

Figure 10 is an enlarged sectional view taken upon the line X—X of Figure 4, looking in the direction of the arrow.

45 Figure 11 is a fragmentary plan view of a card index tray involving a modified form of mechanism for operating the follower block.

Figure 12 is an enlarged sectional view taken upon the line XII—XII of Figure 11 looking in the direction of the arrow.

Figure 13 is a fragmentary enlarged sectional view taken upon the line XIII—XIII of Figure 11.

In describing the invention in relation to the drawings, it will be noted that the tray consists 55 of a bottom plate 1 and a side plate 2 which may

be integral with or secured to the bottom plate. This side plate 2 has an overhanging flange 3 directed inwardly of the tray. Upon the opposite side of the tray there is a side plate 2a to which an overhanging flange 4 is pivotally mounted or hinged as indicated at 5. This flange 4 constitutes a locking means for the retainers and card holders. A coil spring 6 as shown in Figure 4 is associated with the hinged connection 5 in such a manner that it will normally tend to force the flange 4 into the position shown in full lines in Figure 10. The tray is designed to be housed in a cabinet C.

Means are provided for operating the movable flange 4 and in the form shown in Figures 4 and 10, it will be noted that the flange 4 has a depending lug 7 near its forward end. A lever 8 is pivoted adjacent the lower side corner of the tray as indicated at 9 and a link 10 connects the lever 8 with the lug 7. As the lever 8 is elevated as shown in dotted lines in Figure 10, it will swing the flange 4 upwardly so that the card holders may be moved from the tray or inserted therein.

Within the tray and beneath the flanges 3 and 4 are card holder spacing members which are adapted to be longitudinally shifted and compressed by a follower. Different forms of card holder spacing elements have been illustrated and these will now be described.

One form of card holder spacing member is illustrated in Figures 2 and 3 and consists of an inverted channel shaped base 11 which is adapted to extend transversely of the tray. Narrow U-shaped members or clips 12 are attached to the base portion 11 adjacent the ends thereof. These metal strips 12 are shown as provided with projecting tongues 13 which extend through suitable slits in the top of the channel 11 and are crimped over the under side thereof as shown in Figure 2. These metal strips are more or less resilient and are provided with indented portions 14 which are directed inwardly in order to form a restriction through which the card holders can be snapped. These indented portions serve to retain the card holders in the U-shaped bearing clips as will later more fully appear.

In Figures 7 to 9, there is illustrated another form of card holder spacing member which consists of a base portion 18, with upstanding U-shaped metal clips 19 adjacent the ends thereof. These upstanding metal clips 19 have resilient tongues 20 cut from one side thereof and directed inwardly to form a restricted passage for confining the card holders therebeneath. The card

110

holders are adapted to be snapped past these tongues. The U-shaped clips 19 may be welded or secured to the base portion 18 in any suitable manner.

5 A plurality of such card holder spacing members are placed in abutting relation in a tray under the flanges 3 and 4 and are slidably adjusted by means of a follower as will later more fully appear. It will be understood that index 10 cards having card holders with laterally projecting bearing or pintle portions are adapted to be confined in these spacing elements just described. In Figure 5 an index card 21 has been illustrated in elevated position for the purposes of illustration. The index card 21 is removably secured upon a pair of spaced tongues 22a which are struck from a sheet-metal strip 22. This sheet-metal strip 22 has its outer edge curled around a rod 24 which projects beyond the sheet-metal strip and is adapted to be retained in the U-shaped members on the spacing element.

15 Of course, it is understood that any form of card holder having laterally extending pintles may be used and that will fit the bifurcations of 20 a spacing element. The invention is not limited to any specific form of card holder.

25 These card holder spacing elements which retain the card holders are adapted to be held in compressed relation in the tray by means of a 30 follower block. Several forms of follower blocks have been illustrated for thuswise compressing and confining the spacing elements. One form of follower is illustrated in Figure 4 and consists of a plate 25 having an upstanding flange 26 35 which is adapted for contacting the spacing element. A pair of friction levers 27 are pivoted to the plate 25 by means of pins 28 projecting upwardly from the plate and slots 29 in the levers 27. The adjacent ends of the levers 27 are connected by a link 30 having a handle 31 thereon. When the link 30 is swung into alignment with the levers 27, the same are projected outwardly 40 into engagement with the side walls of the tray for frictionally locking the follower plate 25 in position. To release the levers 27 from frictional 45 engagement with the sides of the tray, the link 30 is swung to a position at a right-angle to the levers as shown in dotted lines in Figure 4 for withdrawing the levers from frictional engagement with the sides of the tray. In released 50 position, the follower plate 25 may be longitudinally shifted with respect to the tray.

55 In Figures 11 to 13, a modified form of follower block has been illustrated which is connected with the operating mechanism for the hinged flange 4 of the tray as will now be set forth. It will be noted that the tray has an inclined plate 32 at its forward end. A pair of guide plates 33 are secured to the bottom of the tray beneath the inclined 60 plate 32. The guide plates 33 form a guideway for the follower plate 34. A link 34a is pivoted at one end to the follower plate 34 as indicated at 35. The other end of the link 34 is pivoted to a slide 65 plate 36 which is slidably mounted in a guideway formed by a sheet-metal member 36a having upwardly directed overhanging flanges 37 as shown more clearly in Figure 13. To the slide plates 35, there is hinged a link 38. The link 38 is also hinged to a link 39 which is hinged to the bottom 70 of the tray as indicated at 40. A pair of toggle links 41 connect the plate 39 with the flange 4. The link member 39 has an upstanding handle 42 which may be grasped by the operator for elevating the same. In fact, the links 38 and 39 act as 75 a toggle so that as the handle 42 is elevated the

slide plate 36 will be drawn along guide toward the side of the tray having the hinged flange 4. As the toggle links 38 and 39 are elevated, the flange 4 will be swung upwardly due to the connections 80 41 therewith so that as soon as the flange 4 is swung upwardly for the purpose of unlocking the card holders and spacing elements, the follower block will be simultaneously retracted releasing the compression upon the spacing element so that the same may be quickly and easily removed, or additional ones inserted when it is desired to contract or expand the contents of the tray.

85 When it is desired to remove a card holder from its spacing element, the locking flange 4 is swung upwardly, the card holder may then be lifted from its spacing element. In lifting the card holder from the spacing element it must be forced through the restricted throat formed by the detents 14 or 20, and in forcing the same through such throat the spacing element may be elevated 90 and become dislodged from its position. For this reason, it is preferable to force one or both ends of the card holder above the restricted throat before the locking flange 4 is swung upwardly. Thereafter the card holder may be readily removed from its spacing element without disturbing 95 the same.

100 From the foregoing it will be obvious that a novel form of card index tray has been provided in which each individual card holder is removably 105 retained in a separate bearing or spacing element and in which the retaining and spacing elements are freely mounted for longitudinal adjustment thereof. It will further be appreciated that the 110 spacing elements and card holders are normally locked in the tray against removal by the hinged flange 4, and the compressor plate, and that as soon as the hinged locking plate, or flange 4 is 115 swung upwardly according to the manner shown in Figure 11, the card holders may be removed 120 from or inserted in the spacing and retaining elements. It will also be appreciated that by providing resilient tongues or depressions upon the walls of the bifurcations of the spacing elements, the card holders will be securely held from accidental displacement.

125 I am aware that many changes may be made and numerous details of construction may be varied through a wide range without departing from the principles of this invention, and I, therefore, do not purpose limiting the patent granted hereon otherwise than necessitated by the appended claims.

130 I claim as my invention:

1. In a card index tray, a plurality of spacing 130 and retaining elements longitudinally adjustable of the tray, a follower plate associated therewith, a hinged member on the tray for confining said elements against removal, and means for simultaneously operating said follower and hinge member.

135 2. The combination with a card index tray, of means for locking index cards against longitudinal shifting movement in said tray, means for locking said index cards against upward movement in the tray, and mechanism for simultaneously controlling both of said means.

140 3. In a card index, a tray, a plurality of spacing bars having upwardly extending U-shaped sockets slidably mounted therein, a follower for maintaining said bars in contacting relation, the walls of said U-shaped sockets embodying means adapted for releasably retaining card holders 145 therein, and pivoted locking means on said tray 150

- for normally locking said bars against outward tilting movement.
4. In a card index, a tray, a plurality of card holder retaining bars having U-shaped card holder sockets mounted in said tray, the walls of said sockets having restricted portions for releasably confining the holders therein, and a follower in said tray for maintaining said bars in contacting relation.
- 10 5. In a card index, a tray, a plurality of card holder retaining bars in said tray, a follower associated with said bars, a locking member engaging over the adjacent ends of said bars, and means connecting said member and follower for simultaneous operation.
- 15 6. In a card index, a spacing element having a plurality of pairs of upstanding parts forming pockets adapted for receiving card holders, said upstanding parts embodying means for forming intermediate restricted passages for the purpose set forth.
- 20 7. In a card index, a tray, a plurality of spacing elements therein and longitudinally adjustable of the tray, a follower for compressing said elements, 25 card holders retained by said elements, and a locking member on said tray adapted for extending over the margins of said spacing elements upon one side for retaining the card holders in said elements, said locking member being operable for the removal of said holders from said elements.
- 25 8. In a card index, a tray, a plurality of bars mounted in said tray for longitudinal adjustment thereof, said bars having means for releasably retaining card holders therein, a follower associated with said bars, a hinged member on said tray for engaging over the ends of the bars upon one side of the tray, a guideway in said tray, a plate 30 slideable in said guideway, a connection between said plate and follower and a connection between said plate and hinge member.
- 35 45 50 55 60 65 70 75 80 85 90 95 100 105 110 115 120 125 130 135 140 145 150
9. In a card index, a tray, a plurality of card holder mountings in said tray and longitudinally adjustable thereof, a follower associated with said mountings, a movable locking member on said tray for engaging over the ends of the mountings upon one side of said tray and a connection between said follower and locking member whereby the same may be simultaneously operated.
10. In a card index, a tray, a retaining and spacing element mounted in said tray and having pairs of upstanding parts, each pair of parts having a restricted passage, a card holder mounted between said parts beneath said restricted passages, and a hinged locking flange on said tray for engaging over one end of said element and preventing the escape of said card holder when one end has been elevated above a restricted passage.
11. In a card index, a bar having pairs of upstanding parts, said parts having resilient means forming a restricted throat, a card holder mounted between said parts and adapted to be snapped through the restricted throat.
12. In a card index, a tray, a spacing and retaining element extending transversely of said tray, said element having means for retaining a card holder in normal or partially removed position and a locking flange movably secured to said tray and engaging over an end of said element and retaining said element against upward movement, when said card holder is moved from normal to partially removed position.
13. In a card index, a spacing and retaining element having spaced parts, said parts extending toward each other at a predetermined point to provide a restricted throat and a metal card holding bar confined between said parts and prevented from accidental removal by said restricted throat.
- PAUL O. UNGER. 115
